METHOD OF SHUTTING OFF WATER SANDS
IN WELLS

Thomas W. Pew, Houston, Tex.

Application April 24, 1935, Serial No. 17,995

8 Claims. (Cl. 166—21)

My invention relates to methods of closing off the entrance of water to an oil or gas well from water sands adjacent the oil and gas sands.

In the drilling of wells for oil and gas it is the usual custom to drill the well down to producing sand and set a casing above the sand and then drill thru into the oil or gas sand. In doing this it rather frequently happens that the bit penetrates water sands adjacent to the oil and gas sands so that water coming into the well from the said water sands mixes with the oil from the oil and gas sand and interferes with the flow of the oil from the well, and in many cases practically kills the well so that it will no longer flow.

Where the well is drilled through the producing sand into water sand below the oil and gas sand it has been common to introduce cement into the well to fill the same up above the water sand so as to close off the water. Thus a cement plug is formed in the bottom of the well extending up somewhat above the level of the water sand and so filling the well that no water can enter. This use of a cement plug is only temporarily successful for the reason that water will gradually seep upwardly around the cement plug and finally get access to the oil and gas stratum and eventually flow in in sufficient volume to kill the well.

It is an object of my invention to provide a method of cementing off the water sands so that they will be closed against the entrance of water therefrom to the well bore and the seeping of the water around the cement into the well will be avoided.

I desire to introduce cement into the water stratum and force the same deeply into the sands around the well bore and by filling up the pores and interstices in the water sand adjacent the well bore to thus prevent the entrance of water to the well or to the oil and gas sands adjacent thereto.

The method may be employed wherever water bearing strata are encountered in the drilling of the well.

In the drawing herewith, Fig. 1 is a central vertical section through a well equipped with the usual casing and tubing.

Fig. 2 is a similar view showing the lower end of the apparatus with the water sand cemented off.

In the drawing I have shown a situation in an oil well wherein my invention may be carried out. I have shown the well 1 as extending downwardly through the overlying earth stratum 2, and

through an oil stratum 3. Below the oil stratum 3 is shown a stratum 4, which may or may not be present, and consists of shale, gumbo, or the like, and below this stratum is a water sand 5. The well is shown as having therein a casing 6 at the lower end of which is a casing shoe 7. At the upper end of the casing is a casing head 8 having a laterally extending pipe 9 controlled by a valve 10 through which fluid may enter or pass out of the well. The upper end of the casing head is shown as being threaded to receive a bonnet 11 with a stuffing box 12 at the upper end thereof to seal about the well tubing or flow line 13.

The tubing 13 is shown as being equipped with a cross 14 at the upper end, said cross having two of its outlets closed by bull plugs 15. The other outlet is equipped with a pipe 16, with a valve 17 therein, said pipe acting as a flow line during the operation of the well but which may also serve as a means of pumping liquid into the well during the carrying out of the invention.

I have found that when the water is pumped into the bottom of the well where both oil and water sands are exposed, the water will penetrate and flow away from the well into the water sand much more easily than it will penetrate the oil and gas sand. It may be forced into the water sand at a comparatively low pressure which will not be entirely sufficient to force it into the oil sand.

In carrying out my invention therefore I close off the water sand 5 by filling said sand with cement. I do this by first washing the water sand with clear water and forcing the water radially away from the well bore and into the water sands until the pores and interstices of the sand stratum are opened up and cleaned of material tending to clog the same.

In carrying out this invention I first have the well bore filled with mud or other fluid indicated at 18 of sufficient amount to balance the rock pressure. The tubing or flow line 13 is extended downwardly to a point adjacent the bottom of the well and into the vicinity of the water sand. I introduce water to the bottom of the well through the tubing and raise the column of mud to a point above the water sand and this may be approximately one hundred feet of water in the bottom of the well. The upper end of the well casing is then closed by shutting in the valve 10. Fresh water is then forced in through the tubing under pressure and said water will flow outwardly through the water sands as previously noted. This washing of the sand is continued

for a sufficient period to thoroughly wash the sand around the well bore. The amount of water pumped will depend upon the porosity of the sand and the thickness of the stratum and other conditions. The pumping is continued until the pressure at which the water stratum is taking water is reduced due to the washing effect in the sand, or until enough water has been pumped to thoroughly wash the sand which is to be cemented. The cement is then pumped in through the tubing to the bottom of the well. I contemplate using the usual hydraulic cement employed in cementing wells. The cement slurry is mixed thin at first so that the weight of the cement will be between thirteen and fourteen pounds per gallon. The amount of cement will be sufficient to thoroughly permeate the sands surrounding the well bore. The amount will depend upon the judgment of the operator and he will be influenced by the pressures encountered in forcing the water into the formation and the thickness of the sand to be cemented. The amount might be from fifty to several hundred sacks.

25 After the cement has been pumped into the tubing mud is pumped in following it to displace the cement out of the tubing and into the water stratum so as to thoroughly penetrate the same on all sides.

30 During the operation of the cementing, I contemplate moving the tubing 13 up and down in the well so that the bottom of the tubing is not higher than the top of the water sand, so as to prevent the cement from hardening around the lower end of the tubing and also to distribute the cement equally in all directions. When all the cement has been displaced from the tubing by the mud, the bottom end of the tubing is raised above the water sand, the pump is shut down, and the valve 10 is opened slightly to operate as a choke and allow the pressure to be gradually relieved. This is done slowly to prevent the cement from flowing back from the formation into the well. When the pressure has dropped several hundred pounds the pump is again started and mud is circulated in the well for a period of about thirty minutes, maintaining a back pressure on the well of several hundred pounds by pinching the valve 10, the tubing being worked up and down during this period. The bottom end of the tubing is maintained at a height not closer than four feet to the highest point where the cement has entered the formation. This washes any cement from the hole which may flow back when the pressure is relieved on the casing.

After the mud has circulated in the well in this manner for a period of about one-half an hour, the casing may be opened wide and the pumping continued until mud returns are had from the well bottom. The tubing is then pulled from the hole. The hole is kept full of mud and the cement is allowed to set for about seventy-two hours.

The water sand will thus be completely closed off so that a continued production of oil and gas from the well thereafter will not be interfered with by the water from the water stratum.

Although I have disclosed my invention as being carried out where the water sand is below the oil sand, it is to be understood that it is possible to carry out the invention even where there is oil sand below the water sand. This is possible where the water is due to a leaky casing or failure of the cement to cut off the water sands above. In each case the process is car-

ried out in practically the same manner until the water sands have been thoroughly filled with cement which penetrates deeply into the water sand and prevents the flow of water into the vicinity of the well.

5 In Fig. 2 I have shown the well as it appears after the cement shown at 19 has penetrated the water sands, and filled the lower end of the well bore. The tubing in this view is shown as raised to a level above the cement and in position for 10 flowing the well from the oil and gas sand adjacent thereto.

By means of this method I am enabled to prevent the interference of water with the production of oil and gas from the well so that the 15 well may be operated not only more economically but for a materially longer period of time before it becomes necessary to pump the same. The value of the invention will be apparent to those skilled in the art.

20 What is claimed is:

1. A method of closing off water sands from an oil and gas well including, filling the well with mud, introducing water into the lower end of said well to raise the head of mud away from 25 the water sand stratum, closing up the upper end of the well, forcing water under pressure into said water sand only and washing the same, leaving the oil sands undisturbed, pumping fluid cement under pressure into the washed water 30 sand and forcing said cement deeply into the water sand radially away from the well bore, and holding said cement in position until it hardens.

2. A method of closing off water sands from an oil and gas well including, filling the well with 35 mud, introducing water into the lower end of said well to raise the head of mud away from the water sand stratum, closing off the upper end of the well, forcing water under pressure into said water sand and washing the same, 40 pumping fluid cement under pressure into the washed water sand and forcing said cement deeply into the water sand radially away from the well bore, continuing the pressure upon the cement and circulating mud in the well, and 45 then gradually relieving the pressure and cleaning the well, and holding said cement in position until it hardens.

3. In a well having oil and water sands closely adjacent to each other, the method of cutting off the entrance to the well of water from said water sands, including forcing water under pressure into the water sands to wash the pores and interstices thereof, the pressure being insufficient to force the water into said oil sand, following 50 said water with fluid cementitious material to fill the said water sand deeply into the water stratum with said cementitious material, holding 55 said cement in said sand until it sets and then washing the well.

4. A method of cementing off water sands in wells comprising forcing water under pressure into said sands to wash the pores and interstices thereof, then forcing hydraulic cement under pressure deeply into said sands to close the pores and interstices thereof, maintaining said 60 cement in position until it hardens, circulating fluid in the well until the hole is free of cement and then washing said well.

5. The method of closing off the entrance to a 70 well from water producing sands lying adjacent oil and gas sands, which consists in feeding water through a tube under pressure sufficient to penetrate deeply into the water sands but insufficient to penetrate the oil sands whereby to wash 75

5 the water sands in the vicinity surrounding the well bore, forcing hydraulic cement through a tube under pressure sufficient to penetrate the washed water sands but insufficient to penetrate the oil sands, and maintaining pressure in the well bore to hold the cement in the water sands until it hardens.

6. In a well having water producing sands lying adjacent to oil and gas sands, the method of 10 closing off the entrance of water to the well from said water producing sands including feeding water through a flow tube having its lower end in the water sands deeply into the water sands to wash the same in the vicinity surrounding the 15 well bore, forcing hydraulic cement through the flow tube to deeply penetrate the water sands, maintaining fluid pressure in the well bore to hold the cement in the water sands until it hardens, and before the cement hardens raising 20 the flow tube so that its lower end is above the water sands.

7. In a well having water sands and oil and gas sands discharging fluid into the bore of the well, the method of holding back the oil and 25 gas and permanently closing off the water from entrance into the well, which includes filling the well with mud, introducing water under pressure below the mud, keeping the upper discharge end of the well open until the mud is raised by the 30 water to a level above the water sands, closing the upper end of the well so that the mud con-

stitutes a barrier for preventing the escape of the water into the oil and gas sands, continuing the introduction of water into the water sands to wash the same, then forcing liquid cementitious material into the pores and interstices of said water sands to fill the same with said material, and holding the cementitious material in place until it hardens.

8. In a well having water sands and oil and gas sands, the method of closing off the entrance 10 of water to the oil and gas sands including filling the well with mud, introducing water through a flow tube below the mud, keeping the upper discharge end of the well open until the mud is raised by the water to a level above the water sands, closing the upper end of the well so that the mud provides a barrier for preventing the entrance of the water into the oil and gas sands, continuing the introduction of water into the water sands to wash the same, then forcing liquid 15 cementitious material through said flow tube into the pores and interstices of said water sands to fill the same with said material, maintaining fluid pressure in the well to hold the cement in the water sands until it hardens, before the cement 20 hardens raising the flow tube so that its lower end is adjacent the oil and gas sands, and then releasing the fluid pressure and withdrawing the mud from the well so that the oil and gas may 25 be removed.
